UNITED STATES PATENT OFFICE.

WILHELM MAX ROCKSTROH, OF KLEIN-SEDLITZ, GERMANY.

ABRADING-TOOL.

SPECIFICATION forming part of Letters Patent No. 699,242, dated May 6, 1902.

Application filed August 26, 1901. Serial No. 73,396. (No model.)

To all whom it may concern:

Be it known that I, WILHELM MAX ROCKSTROH, factory director, a subject of the Emperor of Germany, residing at Klein-Sedlitz, 5 near Pirna-on-the-Elbe, in the German Empire, have invented certain new and useful Improvements in Abrading-Tools, of which the following is a complete specification.

Ordinary emery-tools or emery-pads used 10 in workshops have many disadvantages. In the case of the former the emery-cloth is sometimes placed completely around the tool and held by the hand, so that a portion of the cloth is rendered useless. In the case of em- 15 ery-pads often they can be used but once, since they are subject to great wear and the grains of emery do not hold so well on the wood as on the cloth. Polishing by oiling the work and distributing emery-powder thereon, 20 which is then brought into closer contact with the work by means of wooden pads, has sometimes been resorted to, but possesses certain disadvantages.

This invention relates to an abrading-tool 25 which obviates the before-mentioned disadvantages, since a suitably wide strip of emery-cloth is connected to the working surface of the tool and can be easily removed in a simple manner and other strips substituted 30 therefor.

A tool made according to this invention is shown in the accompanying drawings, in which—

Figure 1 shows the tool with the holding 35 device for the strip of emery-cloth open. Fig. 2 shows the same with the emery-cloth therein. Fig. 3 is a longitudinal section. Fig. 4 is a plan; and Fig. 5, a plan, partially in section.

40 *a* is a piece of wood formed with a handle at one end provided with a recess in which the clamp-jaws *b* and *c* are placed. The lower jaw *b* swings about a hinge *d*, while the jaw *c* moves like tongs about a pin *f*, which passes 45 through the two jaws. The upper jaw *c*, which is formed as a double-armed lever, is movably connected to the inner end of a pin *g*, which passes through a recess in the wood *a*. When pressure is applied to the spring- 50 lever *i* on the wood *a*, the pin *g*, and with it the arm *k* of the jaw *c*, is pressed downwardly until the pin *g* acts on the jaw *b* and the lat-

ter rotates about the hinge *d*, so that the jaws are moved apart. One end of the strip of emery-cloth *z* is then folded around the plate *m*, which is located at the forward end of the wooden block *a* and may be provided with teeth which pass through the cloth. At the other end the emery-cloth is placed between the clamp-jaws *b* and *c*, which are preferably 55 also provided with teeth. The pressure on the spring-lever *i* is then released, whereupon it rises and draws the pin *g* with it, since the latter is held in a slot in the lever *i*. The clamp-jaws move back into the recess when 60 the cloth has been stretched. By this means the cloth is tightly drawn around the edge *o* of the wood *a* and is consequently properly stretched. The spring *p* serves for increasing the tension on the pin *g* when the jaws 70 are open.

As will be evident, instead of emery-cloth other material may be used—as, for example, sand or glass paper.

Having now particularly described and as- 75 certained the nature of the said invention and in what manner the same is to be performed, I declare that what I claim is—

1. In a device of the character described, the combination with a holder, of a pair of 80 clamping-jaws carried thereby and adapted to detachably clamp one end of a strip of abrading material and means adapted to detachably secure the other end of said strip of material, as and for the purpose set forth. 85

2. In a device of the character described, the combination with a holder, of a pair of 90 clamping-jaws carried thereby and adapted to detachably clamp one end of a strip of abrading material, means carried by the holder adapted to operate upon said jaws to open them and means carried by the holder adapted to detachably secure the other end of said strip of material, for the purpose set forth. 95

3. In a device of the character described, the combination with a holder, of a pair of 100 clamping-jaws carried thereby, an operating-lever carried by the holder, a pin carried by the lever and connected with one of the clamping-jaws and the inner end of said pin being adapted to operate upon the other clamping-jaw when the operating-lever is depressed whereby to cause the jaws to open to receive

one end of a strip of abrading material and means carried by the holder adapted to detachably secure the opposite end of said strip of material for the purpose set forth.

5 4. In a device of the character described, the combination with a holder, a pair of clamping-jaws carried thereby, an operating-lever carried by the holder, a pin carried by said lever and connected at its inner end with one 10 of said clamping-jaws, said pin being adapted to also operate upon the other jaw when the operating-lever is depressed whereby to cause the jaws to open to receive one end of a strip of abrading material, a spring secured

at one end to one of said jaws and bearing 15 upon the inner end of the pin to normally force the same in a direction to effect the closing of the jaws and means carried by the holder adapted to detachably secure the other end of said strip of abrading material for the 20 purpose specified.

In witness whereof I have hereunto set my hand in presence of two witnesses.

WILHELM MAX ROCKSTROH.
